GOLF CART HANDLE GRIP

Anthony T. Zagwyn, Delavan, Wis., assignor to A. J. Industries Corporation, Delavan, Wis., a corporation of Wisconsin

Filed Aug. 8, 1968, Ser. No. 13,060

Term of patent 14 years

Int. Cl. D8—03

U.S. Cl. D8—138

The handle shown in broken lines in FIGURE 1 is included for illustrative purposes only.

I claim:

The ornamental design for a golf cart handle grip, as shown and described.
